PROCESS AND APPARATUS FOR HANDLING
CORRUGATED CONDUITSHubert E. Snyder, Elmira, N. Y., assignor to The
American Rolling Mill Company, Middletown,
Ohio, a corporation of Ohio

Application December 21, 1932, Serial No. 648,314

9 Claims. (Cl. 61—16)

One source of the great strength of corrugated culverts lies in the resiliency of the metal to accommodate itself to the earth which is packed about it, so that the side pressure may become 5 adequate enough to give the culvert lateral support whereby the arch construction is effective in supporting very heavy top loads. The sidewise expansion of the culvert in seeking lateral support is obviously accompanied by a shortening of 10 its vertical axis. Where adequate lateral support is given without too great lateral expansion, excellent results are obtained; but if the earth is packed loosely about the culvert, or if the horizontal axis of the culvert has to be elongated 15 very greatly before adequate lateral support is given, then the top arch of the culvert becomes flattened and thereby loses some of its inherent strength. These considerations indicate the advisability of installing a culvert in such a 20 way that its vertical axis is longer than its horizontal axis, and employing a culvert of initially somewhat oval shape. In an oval culvert installed with its major axis vertical, such lateral expansion as occurs will merely tend to bring the 25 culvert into round and will not impair the strength of the arch. Additionally, oval shaped culverts or conduits are frequently desirable for other reasons; and one situation in which the elliptical culvert may advantageously be used is 30 in the production of pedestrian under passes for railroads, roadways and the like. Particularly therefore in the larger sizes of culvert, there are distinct advantages in the oval shape.

My invention relates to the production of oval conduits and more particularly to means for distorting a corrugated conduit out of round, at 35 least during the installation thereof.

It is an object of my invention to provide means and a method of distorting culvert out of round, 40 which are extremely simple and inexpensive and do not require the employment of skilled labor.

It is an object of my invention to provide a method of producing elliptical conduit which may be employed at the point of manufacture, and 45 which may serve during the shipment and ultimate installation of the conduit to maintain it in the desired elliptical form.

These and other objects of my invention which will be set forth hereinafter, or will be apparent 50 to one skilled in the art upon reading these specifications, I accomplish by that certain construction and arrangement of parts, and in that process of which I shall now describe a preferred embodiment.

55 Reference is made to the drawing wherein:—

Figure 1 is an end elevation of a conduit treated in accordance with my procedure.

Figure 2, is a horizontal sectional view of a conduit having wire tying means.

Figure 3 is a horizontal section of conduit having removable mechanical means for effecting the desired distortion.

Briefly in the practice of my invention, I provide internal contracting means which engage with or through the walls of a conduit and will 10 serve to fore-shorten an axis thereof, which axis in the installation of the conduit will preferably be the horizontal axis.

In Figure 2, I have indicated holes 1 in the 15 valleys 2 of a corrugated conduit indicated generally at 3. Pairs of these holes are located preferably at diametrically opposed portions of the conduit. The holes are preferably, although not necessarily, placed in the conduit at the time of manufacture, and may if desired, be placed 20 in the sheet metal prior to the galvanizing process. Opposite pairs of these holes are connected by a wire tie 4, which may consist of one or more wires, and usually will comprise at least one wire 25 forming a loop through each of the pairs of holes, the ends of the wire being fastened together within the conduit. I have shown the wire outside 30 of the conduit engaging at least one ridge of the corrugations. Inside the culvert, a bar or stick may be placed between the parallel wires and 35 turned, thus tightening the wires by twisting them and drawing the sides of the culvert toward each other. Sets of the wires 4 will be placed along the length of the conduit at intervals as desired, so as to distort the culvert evenly and uniformly by fore-shortening its horizontal axis and lengthening its vertical axis. The work may 40 be done either at the time of the manufacture of the culvert or at the time of installation, and in either event does not require highly skilled labor, complex apparatus or a great length of time.

The operation of distorting the culvert may be assisted by some inside expanding member or by some outside contracting member if so desired, but this is not necessary. The ties will 45 maintain the conduit in the desired distorted form, and after the installation of the conduit may be removed or not, as desired. In this way, I have provided a means and method for the purpose described, which does not involve the use 50 or wastage of great quantities of extra material nor dunnage which must be moved from job to job.

Figures 1 and 3 show the use of draw bars and 55 turn buckles for essentially the same purpose.

Holes may similarly be put in the valleys of the corrugations of a conduit to be handled in this way; but the number of holes may be reduced. Hooks or brackets 7, which are curved as at 8, 5 to form a means for engaging the crests of the corrugations, are pivotally attached to the rods 10. The rods 10 are threaded and are connected by a turn buckle or similar device 11, which may be rotated to tighten the rods. After the 10 devices have been set into position as shown in Figure 3, the turn buckles may be rotated and the sides of the conduit are drawn together, distorting the culvert as indicated in Figure 1, where the solid lines show the distorted elliptical 15 culvert, and the dotted lines the original circular shape thereof.

As in the case of the wires, all of this work may be accomplished in the field, and after the installation of the culvert, the contracting members 20 may be removed therefrom. It will be the usual practice to distort the culvert out of round, install it in the desired position with its major or longer axis vertical, fill in about the culvert the earth or other material, and when the installation 25 is otherwise completed, remove the contacting members, and allow the culvert sides to expand against the surrounding earth or filling. It will be clear that the devices 7 in Figures 1 and 3, can be unhooked from engagement 30 with the corrugations, and can be removed from the inside of the culvert by giving them a rotary movement.

Having thus described my invention, what I 35 claim as new and desire to secure by Letters Patent is:

1. A process of distorting corrugated conduit 40 out of round, which comprises engaging opposite side portions of said conduit by an internal member extending across said conduit, and drawing said side portions together by a contracting action.

2. A process of distorting corrugated culvert 45 out of round, which comprises engaging oppositely disposed corrugations by members which

pass through holes in the sides of said conduit and drawing said members together.

3. A method of distorting a corrugated conduit 5 to an elliptical cross section, which comprises providing holes in opposite sides thereof, inserting means in these holes to engage ridges of the corrugations internally of the conduit, connecting said means by contracting means and drawing the sides of said conduit toward each other.

4. A method of distorting a conduit out of round which comprises providing interspaced holes in opposite sides thereof, inserting a wire through these holes so that said wire crosses the conduit interiorally thereof, fastening the 10 wire to form a loop and drawing the two sides of said conduit toward each other by twisting said wire.

5. A method of setting a culvert which comprises distorting the culvert so as to increase its 20 vertical axis by an internal contracting member engaging opposite sides thereof, placing the said culvert in position, filling in materials about the sides of said culvert and afterward removing said contracting means.

6. A conduit of elliptical cross section having 25 means for tying opposite sides thereof together for maintaining the elliptical shape, said means lying essentially along the minor axis of the ellipse formed by the conduit in cross section. 30

7. A distorted, out-of-round conduit having internally disposed contracting means connecting opposite side walls.

8. A distorted conduit having internally disposed contracting means connecting opposite 35 side walls, said means comprising wires passing through holes in said walls and twisted to draw said walls toward each other.

9. A distorted conduit having internally disposed contracting means connecting opposite 40 side walls, said means comprising members passing through perforations in the walls of said conduit and engaging at least one ridge of the corrugations internally of said conduit.
